UNITED STATES PATENT OFFICE.

JOSEPH MARION KING, OF JACKSONVILLE, FLORIDA.

FLUID-TRACTOR.

1,119,433.

Specification of Letters Patent.

Patented Dec. 1, 1914.

Application filed May 15, 1912. Serial No. 697,386.

To all whom it may concern:

Be it known that I, JOSEPH MARION KING, a citizen of the United States, residing at Jacksonville, in the county of Duval and State of Florida, have invented certain new and useful Improvements in Fluid-Tractors, of which the following is a specification, reference being had therein to the accompanying drawings.

10 This invention provides a device for producing a flow of liquid and for increasing the efficiency of an engine with which it is associated, this being accomplished by utilization of the energy present in exhaust or other fluids having initial pressure in a manner somewhat similar to that involved in my copending application for patent on fluid tractor, filed April 27, 1912, Serial Number 693,566. The basic principles of 15 fluid action are somewhat similar in this and that application, and reference may be had to the former application for a more extended exposition of those principles than it is necessary to set out herein. Among 20 the differences between the two devices is that the liquid caused to flow by this device is discharged separately from the main portion of the pressure fluids, instead of with all of the pressure fluids as in the device of the 25 former application.

This invention contemplates a fluid-treating device of the character described having a fluid-conduit surrounded longitudinally by an outer casing, there being between the 30 conduit and casing a cooling-space divided into chambers, one of which has communication with the fluid-conduit through a valve-controlled passage, the chambers being in communication with one another through a 35 valve-controlled port, and one of the chambers having a discharge port. Exhaust or other fluids, such as gases from an internal-combustion engine, entering the fluid-conduit of the device as a motive medium will 40 be so affected or modified that partial vacuums will be produced in the device, whereby there is caused a flow of fluid distinct from the motive medium, as water from a cooling-jacket, and whereby an engine or other source of exhaust or motive 45 medium fluids is relieved to a considerable extent of atmospheric and other back pressures and the tendency of the motive me-

dium to flow from the source will be increased.

When read in connection with the description herein, the details of construction and arrangement of parts will be apparent from the accompanying drawings, forming part hereof, wherein an embodiment of the invention susceptible of use with an internal combustion engine is disclosed, for purposes of illustration.

While a preferred form of the invention is shown and described herein, it is to be understood that it is not the intention to be limited necessarily to the precise delineation herein in interpretation of claims hereinafter, as it is obvious that the parts can be variously formed and organized, and adapted for use with other conduits supplying fluids impulsively, within the limits prescribed by the claims, without departing from the nature and spirit of the invention.

Like reference-characters refer to corresponding parts in the views of the drawings, of which—

Figure 1 is an exterior view, with parts broken away; Fig. 2 is a longitudinal sectional view; Fig. 3 is a bisectional view, on the line $x-x$, Fig. 2, looking at the receiving end; and Fig. 4 is a bisectional view, on the line $x-x$, Fig. 2, looking at the discharge end.

Having more particular reference to the drawings, 5 designates an outer casing or shell, preferably circular in cross-section, and contracted at the receiving end A and formed with a threaded portion 6 for connection with an exhaust-conduit leading 10 from an engine. The wall of the outer casing is interiorly extended to form near the discharge end B an annular wall 7, from which extends to the contracted receiving end an inner casing 8, preferably circular 15 in cross-section, constituting a continuous exhaust-passage. The annular space between the casings is a liquid-flow or cooling space. This space, in the embodiment disclosed by the drawings, is divided by an annular wall 9 into what may be called a receiving-chamber 10 and a discharge-chamber 11. These chambers are in communication with each other through a passage 12 formed by an outwardly-extending portion 13 and a 20 cylindrical extension 14 of the outer casing.

The extension 14 is screw threaded to receive a threaded cap 15, in which is formed a guideway 16 for a stem 17 of a valve 18 co-operating with a seat 19 on the outer casing 5 to control the flow of fluids through the passage. The valve 18 is susceptible of opening under the influence of fluid pressure in chamber 10 and of closing under similar influence in chamber 11. The valve 18 preferably is located on top of the device, in order that of its own weight it may have a tendency to close the passage. The threaded cap 15 being removable, easy access may be had to the valve 18 for repairs, replacement, or otherwise.

For the purpose of conducting a portion of the exhaust-fluids entering the receiving end of the device to chamber 10, there is provided a conduit or receiving-passage 20 leading to that chamber and having a receiving end 21 positioned opposite to the receiving end and directly in the path of entering exhaust fluids. The end of the conduit is screw threaded to receive a threaded portion of a member 22, which member has a flared or enlarged rim 23 for directing exhaust-fluids into conduit 20. The member 22 is formed with an interior seat 24, with which an inwardly-opening valve 25 co-operates to close the conduit. This valve has a stem 26 disposed in a guideway 27 of a frame 28 in conduit 20, and interposed between the valve and frame is a spring 29 having a tendency to close the valve. The tension of this spring may be altered by turning the member 22 inwardly or outwardly, and, for use in turning, the member is formed with notches or recesses 30 to receive parts of a suitable turning-tool. The maximum diameter of the member 22 is less than the interior diameter of the threaded coupling portion 6, so that the member and valve may be removed from the device when desired.

45 Liquid is admitted to chamber 10 through an inlet 31 and a conduit 32, with which is associated a check-valve 33 arranged to admit liquid to the chamber. Fluids are discharged from chamber 11 through an outlet 34 and a conduit 35 leading to a reservoir or other desired place of disposal, with which is associated a check-valve 36 arranged to permit flow of fluids from the chamber. The outlet 34 is so positioned below the top 50 of chamber 11 that the proper amount of gas to force liquid therefrom constantly is retained.

The discharge end of the device is formed with a screw-threaded portion upon which 60 is screwed a cap member 37 having a contracted coupling portion 38 for connection with an exhaust-disposal conduit. On wall 7 there is a seat 39, with which an outwardly-opening valve 40 co-operates to close 65 the passage through the device against at-

mospheric pressure, the valve being susceptible of opening under the influence of fluid pressure from within the inner casing 8. The valve is supported and guided by having its stem 41 project into a guideway 70 in a frame 42 positioned in the cap member.

After an engine with which this device is associated has completed an exhaust stroke and exhaust fluids have been discharged through the device, there is a loss in volume 75 or pressure of exhaust fluids in the device because of liberation of heat, and the atmosphere tends to rush back through the exhaust-conduits. Back flow of air is prevented by closing of valve 40 against atmospheric pressure, and the engine thereby is relieved of the disadvantages of atmospheric backlash.

When exhaust fluids enter the device, the major portion thereof is discharged through 85 the main exhaust-passage 8, but impulse of exhaust opens valve 25 and a portion of those fluids is conducted to chamber 10 through conduit 20 and to chamber 11 through passage 12 in sufficient quantity to 90 fill those chambers. Of course, on the initial entrance of exhaust into the device, the latter is cooler than the exhaust, and therefore, a lapse in pressure below that of the atmosphere occurs in the chambers and liquid 95 flows into chamber 10 through inlet 31 in response to the tendency of gases to restore a stable equilibrium. Thereafter, the portion of the exhaust that enters chamber 10 under impulsive action comes into contact 100 with the liquid therein, and that portion of exhaust gases that is susceptible of liquefaction is liquefied, lapse in volume results both from heat reduction and liquefaction, and liquid continues to flow into the chamber 105 through inlet 31. The inertia of the mass of gas entering chamber 10 operates to cause liquid and gaseous fluids to be forced into chamber 11 through passage 12 the valve 18 opening and check-valve 33 in the 110 liquid-supply conduit closing and preventing back flow therein. The sequential lapse in volume of gases remaining in chamber 10 causes a partial vacuum in that chamber and further flow of liquid through inlet 31, 115 the valve 18 being closed at such time. Non-liquefying gases in chamber 10, being lighter than liquid, are in the upper portion of the chamber, and they are forced with the liquid into chamber 11 under exhaust impulse, 120 where their expansion operates to force liquid out through outlet 34, the check-valve 36 preventing back flow when the pressure in chamber 11 is less than that of the atmosphere. When too much gas has accumulated in chamber 11, a portion thereof is forced out through outlet 34 with liquid. The spring of valve 25 is of sufficient tension 125 to prevent its opening in consequence of momentary subsidence of pressure in 130

chamber 10, so that the restoration of pressure balance is brought about by inflow of liquid through inlet 31. The valve 25 also has a tendency to close, of course, under influence of decreases of pressure in the main exhaust-conduit, so that the engine has all the advantage of such decreases of pressure in that conduit. There is cooperation between the atmospheric valve 40 and the 10 liquid-flow or cooling space, in that that space, by its cooling effect, enhances the drawing effect on the engine exhaust-ports; and, also, because of the fact that this drawing effect is enhanced, exhaust impulses have 15 greater force and their effect in the cooling-space increased. During operation, the flow of liquid through the chambers surrounding the casing 8 cools that casing and causes a continuance of intermittent decreases of 20 pressure in the main exhaust-passage, with the attendant advantages previously described.

Having thus described my invention, what I claim as new, and desire to secure by Letters Patent, is—

1. An exhaust-treating device having an exhaust-passage, a liquid-receiving chamber provided with an outlet having associated therewith a valve closing against fluid pressure exterior of the chamber, communicating with said chamber a receiving-passage leading from said exhaust-passage and having a valve susceptible of opening under influence of fluid pressure in said exhaust-passage, and a liquid-supply inlet for said receiving-chamber having associated therewith a valve preventing back flow from said chamber.

2. An exhaust-treating device having an exhaust-passage, a liquid-receiving chamber having a liquid-inlet, a discharge-chamber having an outlet, a passage from said receiving-chamber to said discharge-chamber having a valve susceptible of opening under influence of fluid pressure in said receiving-chamber, communicating with said receiving-chamber a receiving-passage leading from said exhaust-passage and having a valve susceptible of opening under influence of exhaust pressure in said exhaust-passage, and a valve associated with said liquid-inlet of said receiving-chamber preventing back flow from that chamber.

3. An exhaust-treating device having an exhaust-passage, a liquid-flow space, a wall dividing said space into a receiving-chamber and a discharge-chamber, a passage from said receiving-chamber to said discharge-chamber having a valve susceptible of opening under the influence of fluid pressure in said receiving-chamber, an outlet for said discharge-chamber, communicating with said receiving-chamber a receiving-passage leading from said exhaust-passage and having a valve susceptible of opening under the influence of fluid pressure in said receiving-chamber, an outlet for said discharge-chamber, communicating with said receiving-chamber a receiving-passage leading from said exhaust-passage and having

fluence of exhaust pressure in said exhaust-passage, and a liquid-supply inlet for said receiving-chamber having associated therewith a valve preventing back flow from that chamber.

4. An exhaust-treating device having an exhaust-passage, a liquid-receiving chamber having an outlet provided with a valve closing against fluid pressure exterior of said chamber, communicating with said chamber a receiving-passage leading from said exhaust-passage and having an entrance positioned in the path of fluids entering said exhaust-passage adapted to receive impulses of fluids, a valve for said receiving-passage 70 susceptible of opening under such impulses, and a liquid-supply inlet for said chamber having associated therewith a valve preventing back flow from said chamber.

5. An exhaust-treating device having an exhaust-passage, a liquid-receiving chamber having a liquid-inlet, a liquid-discharge chamber having an outlet, a passage from said receiving-chamber to said discharge-chamber having a valve susceptible of opening 80 under the influence of fluid pressure in said receiving-chamber, communicating with said receiving-chamber a receiving-passage leading from said exhaust-passage and having an entrance positioned in the path of 85 fluids entering said exhaust-passage adapted to receive impulses of fluids, a valve for said receiving-passage susceptible of opening under such impulses, and a valve associated with said liquid-inlet of said receiving-chamber preventing back flow from that chamber.

6. An exhaust-treating device having an exhaust-passage, a liquid-flow space, a wall dividing said space into a receiving-chamber and a discharge-chamber, a passage from said receiving-chamber to said discharge-chamber having a valve susceptible of opening under the influence of fluid pressure in said receiving-chamber, an outlet 105 for said discharge-chamber, communicating with said receiving-chamber a receiving-passage leading from said exhaust-passage and having an entrance positioned in the path of fluids entering said exhaust-passage 110 adapted to receive impulses of fluids, a valve for said receiving-passage susceptible of opening under such impulses, and a liquid-supply inlet for said receiving-chamber having associated therewith a valve preventing 115 back flow from that chamber.

7. An exhaust-treating device having an outer casing, an exhaust-conduit therein, there being a cooling-space between said casing and conduit and surrounding the 125 latter and said space including a receiving-chamber, an outlet for said receiving-chamber having associated therewith a valve closing against fluid pressure exterior of said chamber, communicating with said chamber, 130

ber a receiving-passage leading from said conduit and having a valve susceptible of opening under the influence of fluid pressure in said conduit, and a liquid-supply inlet 5 for said chamber having associated therewith a valve preventing back flow from said chamber.

8. An exhaust-treating device having an outer casing, an exhaust-conduit therein, 10 there being a cooling-space between said casing and conduit and surrounding the latter and said space including a receiving-chamber and a discharge-chamber, a passage from said receiving-chamber to said discharge-chamber having a valve susceptible 15 of opening under the influence of fluid pressure in said receiving-chamber, communicating with said receiving-chamber a receiving-passage leading from said conduit having a valve susceptible of opening under 20 the influence of fluid pressure in said conduit, a liquid-supply inlet for said receiving-chamber having associated therewith a valve preventing back flow from that chamber, and an outlet for said discharge-chamber. 25

9. An exhaust-treating device having an outer casing, an exhaust-conduit therein, there being a cooling-space between said casing and conduit and surrounding the latter and said space including a receiving-chamber, an outlet for said receiving-chamber having associated therewith a valve closing against fluid pressure exterior of that 30 chamber, communicating with said chamber a receiving-passage leading from said conduit and having an entrance positioned in the path of fluids entering said conduit adapted to receive impulses of fluids, a valve 35 for said receiving-passage susceptible of opening under such impulses, and a liquid-supply inlet for said receiving-chamber having associated therewith a valve preventing back flow from said chamber. 40

45 10. An exhaust-treating device having an outer casing, an exhaust-conduit therein, there being a cooling-space between said casing and conduit and surrounding the latter and said space including a receiving-chamber and a liquid-discharge chamber, a passage from said receiving-chamber to said discharge-chamber having a valve susceptible 50 of opening under the influence of fluid pressure in said receiving-chamber, communicating with said receiving-chamber a receiving-passage leading from said conduit and having an entrance positioned in the path of fluids entering the conduit adapted to receive impulses of fluids, a valve for 55 said receiving-passage susceptible of opening under such impulses, a liquid-supply inlet for said receiving-chamber having associated therewith a valve preventing back flow from that chamber, and an outlet for 60 said discharge-chamber. 65

11. An exhaust-treating device having in combination an exhaust-passage provided with a valve closing against atmospheric pressure, a liquid-receiving chamber provided with an outlet having associated therewith a valve closing against fluid pressure exterior of said chamber, communicating with said chamber a receiving-passage leading from said exhaust-passage and having a valve susceptible of opening under the influence of fluid pressure in said exhaust-passage, and liquid-supply inlet for said chamber having associated therewith a valve preventing back flow from said chamber. 70

12. An exhaust-treating device having in combination an exhaust-passage provided with a valve closing against atmospheric pressure, a liquid-flow space, a wall dividing said space into a receiving-chamber and a discharge-chamber, a passage from said receiving-chamber to said discharge-chamber having a valve susceptible of opening under the influence of fluid pressure in said receiving-chamber, an outlet for said discharge-chamber, communicating with said receiving-chamber a receiving-passage leading from said exhaust-passage and having a resiliently-closed valve susceptible of opening under the influence of exhaust pressure 95 in said exhaust-passage, and a liquid-supply inlet for said receiving-chamber having associated therewith a valve preventing back flow from that chamber. 90

13. An exhaust-treating device having in combination an exhaust-passage provided with a valve closing against atmospheric pressure, a receiving-chamber having an outlet provided with a valve closing against fluid pressure exterior of said chamber, communicating with said chamber a receiving-passage leading from said exhaust-passage and having an entrance positioned in the path of fluids entering said exhaust-passage adapted to receive impulses of 100 fluids, a resiliently-closed valve for said receiving-passage susceptible of opening under such impulses, and a liquid-supply inlet for said chamber having associated therewith a valve preventing back flow from 110 said chamber. 115

14. An exhaust-treating device having in combination an exhaust-passage provided with a valve closing against atmospheric pressure, a liquid-flow space, a wall dividing 120 said space into a receiving-chamber and a discharge-chamber, a passage from said receiving-chamber to said discharge-chamber having a valve susceptible of opening under the influence of fluid pressure in said receiving-chamber, an outlet for said discharge-chamber, communicating with said receiving-chamber a receiving-passage leading from said exhaust-passage and having an entrance positioned in the path of fluids en- 125 130

- tering said exhaust-passage adapted to receive impulses of fluids, a resiliently-closed valve for said receiving-passage susceptible of opening under such impulses, and a liquid-supply inlet for said receiving-chamber having associated therewith a valve preventing back flow from that chamber.
15. An exhaust-treating device having in combination an outer casing, an exhaust-conduit therein provided with a valve closing against atmospheric pressure, there being a cooling-space between said casing and conduit and surrounding the latter and said space including a receiving-chamber, an outlet for said chamber having associated therewith a valve closing against fluid pressure exterior of said chamber, communicating with said chamber a receiving-passage leading from said conduit and having a resiliently-closed valve susceptible of opening under influence of fluid pressure in said conduit, and a liquid-supply inlet for said chamber having associated therewith a valve preventing back flow from said chamber.
25. 16. An exhaust-treating device having in combination an outer casing, an exhaust-conduit therein provided with a valve closing against atmospheric pressure, there being a cooling-space between said casing and conduit and surrounding the latter and said space including a receiving-chamber and a discharge-chamber, a passage from said receiving-chamber to said discharge chamber having a valve susceptible of opening under influence of fluid pressure in said receiving-chamber, communicating with said receiving-chamber a receiving-passage leading
- from said conduit having a resiliently-closed valve susceptible of opening under the influence of fluid pressure in said conduit, a liquid-supply inlet for said receiving-chamber having associated therewith a valve preventing back flow from that chamber, and an outlet for said discharge-chamber.
17. An exhaust-treating device having in combination an outer casing, an exhaust-conduit therein provided with a valve closing against atmospheric pressure, there being a cooling-space between said casing and conduit and surrounding the latter and said space including a receiving-chamber and a discharge-chamber, a passage from said receiving-chamber to said discharge-chamber having a valve susceptible of opening under the influence of fluid pressure in said receiving-chamber, communicating with said receiving-chamber a receiving-passage leading from said conduit and having an entrance positioned in the path of fluids entering the conduit adapted to receive impulses of fluids, a resiliently-closed valve for said receiving-passage susceptible of opening under such impulses, a liquid-supply inlet for said receiving-chamber having associated therewith a valve preventing back flow from that chamber, and an outlet for said discharge-chamber.

In testimony whereof I affix my signature in presence of two witnesses.

JOSEPH MARION KING.
